LUIS AIMÉ, OF WEST HOBOKEN, NEW JERSEY.

ADJUSTABLE LEG REST FOR CHAIRS.

Application filed May 17, 1922. Serial No. 561,676.

To all whom it may concern:

Be it known that I, Luis Aimé, a citizen of the United States, and a resident of West Hoboken, in the county of Hudson and 5 State of New Jersey, have invented a new and Improved Adjustable Leg Rest for Chairs, of which the following is a full, clear, and exact description.

This invention relates to attachments for 10 chairs and particularly to an improved leg rest for rocking chairs formed to be extended to any desired extent when in use and to be folded and shifted to a position beneath the chair when not in use.

15 The object of the invention is to provide a leg rest which may be positively locked in any of several adjusted positions.

Another object of the invention is to provide an improved simplified construction of 20 leg rest which is comparatively inexpensive and which will effectively act when in use and which may be readily stored beneath the rocking chair when not in use.

Another object, more specifically, is to 25 provide a leg rest for rocking chairs, which when not in use, may be disconnected and folded up after which it is stored beneath the chair in such a manner as to not present an unpleasing appearance.

30 In the accompanying drawing—

Figure 1 is a side view of a leg rest disclosing an embodiment of the invention, the same being shown applied to a rocking chair.

35 Figure 2 is a top plan view of the structure shown in Figure 1, certain parts being broken away.

Figure 3 is a sectional view through Figure 1 on line 3—3, the leg rest being shown 40 folded and stored away.

Figure 4 is an enlarged longitudinal sectional view through the upper adjusting bar shown in Figure 1.

Figure 5 is an enlarged sectional view 45 showing one end of the bar illustrated in Figure 4.

Figure 6 is an enlarged sectional view through Figure 4 on line 6—6.

Referring to the accompanying drawing 50 by numerals, 1 indicates an ordinary rocking chair provided with the usual rockers, seat and legs. In addition to these members, a bar 2 is provided and also a pair of runways 3 secured to one of the back spindles 4 and to a cross brace 5. Connected to the seat 6 at the center of the front and on the

under side are brackets 7 and 8 through which the respective pintles 9 extend, said pintles projecting from a latch 10. This latch is provided with straight sides and a 60 notch 11 as shown in Figures 4 and 5 whereby the hook end 12 may fit over the same against the flat sides and be held in proper position thereby. As the rocking chair moves, this rectangular construction will 65 cause the bar 13 to move back and forth without slipping off of the latch 10.

In order to positively lock the hook 12 in engagement with the latch 10, a sliding bolt 14 is provided and held in place by 70 spring 15 while a thumb member 16 is secured thereto and extends through an opening 17 in the bar 13. The bar 13 may be of any desired shape but is preferably U-shape in cross section as illustrated in Figure 75 6, said bar telescopically fitting into an auxiliary bar 18 U-shape in cross section and provided with inturned flanges 19 which will act as a guide for the bar 13. The auxiliary bar 18 is pivotally mounted at 20 to a cross 80 bar 21 and is held centrally thereof by suitable sleeves 22. The bar 13 is provided with an aperture near one end through which a pin 23 loosely extends, said pin being pressed by a spring 24 so as to always project 85 through the bar 13 and whenever possible snap through one of the openings 25 in bar 18. Preferably, there are several openings 25 in bar 18 whereby there may be a relative movement of the bars 13 and 18 to shift 90 the rod 21 toward or from the chair 1. The rod 21 is mounted in the side standards 26 which side standards are rounded at 27 so as to freely rock. A pad or support 28 is mounted on the upper end of the standards 95 26, said pad or support being connected with the standards by suitable brackets 29 which have pins 30 extending into the standards. The pad or support 28 freely swings on the pins 30 so as to readily adjust itself to the 100 position of the legs of the person using the chair 1.

A hook 31 is secured to the lower surface of pad 28 and is adapted to fit over the latch 10 when the parts are folded and stored 105 away as shown in dotted lines in Figure 1 and also as shown in Figure 3. By this arrangement, the pad or support 28 will act to support the front part of the folded or nested leg rest and also act as a covering 110 member for sliding the various parts from view while the runways 3 will act as a rear

support, said runways being engaged by the sleeves 32 and 33 mounted on the rod 34, which rod connects the standards at the lower end. Pivots mounted on these rods 5 are spaced bars 35 and 36 which bars are brought together and pivotally connected at 37 to the single bracing bar 38. A transverse section 39 is provided and adapted to fit into the notch 40 for limiting the downward swinging movement of the bars 35 and 36 when the parts are in the position shown in Figure 1. The bracing bar 38 is provided with a number of openings 41 adapted to accommodate the rod 2 wherever the position of the lower ends of the standards 26 may be changed so that the lower ends of the standards may be moved toward or from the rocking chair 1.

When the lower ends of the standards 20 have been adjusted, the bars 13 and 18 are also adjusted to cause the standards to assume a proper angle as shown in Figure 1. In order to adjust the effective length of the bar 38, the same must be lifted up and 25 moved longitudinally to cause one of the other notches 41 to accommodate rod 2 while to adjust the bars 13 and 18 it is only necessary to depress the pin 23 and move the bars together or apart as the case may 30 be until the pin has snapped into the next aperture 25. This provides an easy, simple and yet strong adjusting structure.

What I claim is:—

1. The combination with an adjustable leg rest for chairs, of a bracing member 35 connected with the leg rest at its lower end and adapted to be connected with the chair, a pair of telescoping members connected respectively to the leg rest and the chair, said 40 telescoping members being provided with means for locking the members against inde-

pendent movement, one of said members being provided with a hook having a substantially rectangular socket, means pivotally mounted on said chair formed with parallel 45 sides adapted to snugly fit in said socket, and a bolt on the bracing member provided with said hook for locking the socket to said means.

2. In combination with an adjustable leg 50 rest for chairs, a brace pivotally connected to the upper part of the leg rest, said brace being adapted to be connected to the chair, a hook presenting a substantially rectangular socket forming a part of said brace at 55 the outer end thereof, a latch mounted on the chair and provided with parallel sides and a notch, said latch fitting said socket, a slidably member carried by said brace adjacent said hook end, a spring acting on said 60 member, said member being adapted to be slid in said notch in said latch to prevent the disengagement of the socket from the latch.

3. In combination with a chair and a leg 65 rest therefor, a telescoping brace pivoted to the leg rest and engageable with the chair, one section of the telescoping brace being provided with a plurality of openings at spaced relation from each other, a flexible 70 element secured at one end of the other section of said telescoping brace, a stud adapted to project through said opening carried at the free end of the flexible element, said stud locking said sections in position, a 75 pivoted latch member secured to the under surface of the chair, a hooked member formed at the outer end of said section carrying said stud, and means adjacent said hook adapted to engage said pivoted latch 80 when said hook straddles the latch.

LUIS AIME.
